UNITED STATES PATENT OFFICE.

CHARLES PRENTICE TURNER, OF STEELTON, PENNSYLVANIA.

VALVE-OPERATING MECHANISM FOR REGENERATIVE FURNACES.

Application filed November 2, 1921. Serial No. 512,304.

To all whom it may concern:

Be it known that I, CHARLES PRENTICE TURNER, a citizen of the United States, and residing at Steelton, Dauphin County, State 5 of Pennsylvania, have invented certain new and useful Improvements in Valve-Operating Mechanism for Regenerative Furnaces, of which the following is a specification.

The present invention relates to mechanism 10 for operating the reversing valves of regenerative furnaces.

In the usual operation of regenerative furnaces, particularly open hearth furnaces, a combustible gas, such as producer 15 gas, and atmospheric air, are led through separate channels or conduits to the hearth or combustion chamber, where they are allowed to intermingle and where combustion of the gas takes place. The hot gases of 20 combustion pass from the opposite end of the furnace through two similar conduits to the stack or first to one or more waste-heat boilers and thence to the stack. Valves are provided by means of which the direction 25 of flow of air and gas to the furnace and the flow of hot waste gases therefrom may be controlled or reversed, and a checker chamber is provided in each of the gas conduits, the brick checkerwork in these chambers be- 30 ing heated to high temperatures when the exhaust gases from the furnace are passing therethrough, and serving to heat the incoming gas and air when the direction of gas flow has been reversed.

A serious difficulty met with in furnaces 35 of this character resides in the tendency for explosions of considerable magnitude to occur at the time of reversal. These explosions are due to the fact that at each reversal 40 of the furnace, a considerable quantity of unburned gas, which has been highly heated in the checker chamber but has not yet reached the combustion chamber, flows toward the stack and is mixed with a quantity 45 of highly heated air, the intermingling of these two gases causing their sudden ignition or detonation. In modern open hearth furnaces waste heat boilers are frequently used, through which the hot gases of combustion 50 are passed before they flow to the stack to escape to the atmosphere, and by means of which a considerable saving of heat is effected. Where such boilers are employed the explosion of unburned gas upon 55 a reversal of the furnace is particularly un-

desirable in that the boiler settings, brick work and connecting flues, may be seriously damaged.

It has been found that these explosions may be avoided if the hot unburned gas is 60 allowed to flow through the boiler to the stack before the air conduit is opened, upon each reversal of the furnace, so that no intermixture of hot gas and air can take place, unless it takes place in the stack, 65 where, if there actually is an explosion, it is harmless in effect. In accordance with this method of operation, at each reversal of the furnace, the valve controlling the flow of heated air to the stack is the last to be 70 opened, and is only opened after the unburned gases have made their escape.

The object of this invention is to provide a mechanism for conveniently accomplishing the reversal of a regenerative furnace 75 and by means of which the valves are opened and closed in the necessary sequence to prevent all explosions. Electro-mechanical valve operating devices are provided which are controlled by a single master 80 switch, the operation of this master switch by the furnace attendant at the desired time being all that is necessary to effect the reversal of the furnace.

Each valve is provided with an individual electro-mechanical valve operating device and circuit making and breaking mechanism controlled by the master switch automatically opens and closes the circuits 85 to the several valve operating devices so that these are energized and deenergized in the desired sequence. In my co-pending application, Serial No. 512,303 filed Nov. 2, 1921, an apparatus is described in which a single motor is provided for operating all 90 of the valves, this motor being connected to the valves mechanically and being controlled by a single master switch, as in the present instance. In some cases it is im- 95 possible or undesirable to employ a mechanism as outlined above and described in my co-pending application, inasmuch as the mechanical difficulties of connecting all of the valves to the single operating motor are too great. In such cases the individual 100 valve operating devices described in the present application are particularly useful.

The present mechanism has many novel features, as will be apparent to one skilled 110 in the art, as it is disclosed in the following

description and in the accompanying drawings in which:

Figure 1 is a plan view of the gas intake and outlet passages of a regenerative open hearth furnace, portions being broken away to show the interior of the checker chambers and flues;

Figures 2, 3 and 4 are sections on lines 2-2, 3-3 and 4-4, respectively, of Figure 1;

Figure 5 is a side elevation of a valve and the valve operating mechanism associated therewith;

Figure 6 is an end view of the same;

Figure 7 is a side view of circuit making and breaking mechanism controlling the circuits to the individual valve operating motors;

Figures 8, 9 and 10 are sections on lines 8-8, 9-9, and 10-10, respectively of Figure 7;

Figure 11 is a diagrammatic representation of certain motor control circuits;

Figure 12 is a series of diagrams, showing the circuits through the various valve operating motors, and the sequence in which such circuits are established in the operation of the mechanism;

Figure 13 is a side elevation of a valve and a modified form of valve operating mechanism;

Figure 14 is an end view of the same;

Figure 15 is an enlarged view of a motion stopping mechanism adapted to be used with the valve operating device shown in Figure 13;

Figure 16 is a side elevation of a device for opening and closing in predetermined sequence circuits through the several modified valve operating devices;

Figures 17, 18 and 19 are sections on lines 17-17, 18-18 and 19-19 respectively of Figure 16;

Figure 20 is a diagram showing the arrangement of certain electrical circuits;

Figure 21 is also a diagram showing the arrangement of circuits and parts for modifying the operation of the circuit opening and closing device illustrated in Figure 16, and

Figure 22 is a series of diagrams showing the positions of the valves and the sequence of establishment of circuits through the individual valve operating devices, in successive steps, which will result from the use of the modified apparatus illustrated in Figures 13 to 20 inclusive.

The hearth, or chamber in which the gases are actually burned is not illustrated in the drawings but it will be understood that the horizontal flues 10, 11, 12 and 13 are the gas and air conducting flues, flues 10 and 13 being the gas flues and flues 11 and 12 the air flues, and that each flue is adapted to conduct its gaseous contents in either direc-

tion. Enlargements 10', 11', 12' and 13' constitute chambers for containing the usual checker work, which is not shown. The flow of gases through the respective flues is controlled by valves which are illustrated diagrammatically in Figure 1 and indicated at G^r, G^s, A^s, A^r, A'^r, A'^s, G'^s, and G'^r, respectively. The main gas intake is illustrated at 14 and is connected by flues 15 and 16 to flues 10 and 13, respectively, the direction of flow of gas being controlled by valves G^r and G'^r. The stack is indicated at 17 and flues 18 and 19 respectively connect each of the four flues 10, 11, 12 and 13 to this stack, the valves G^s, A^s, A'^s, and G'^s controlling the openings between the last mentioned flues and flues 18 and 19. Valves A^r and A'^r control the flow of fresh air into flues 11 and 12.

In the tops of flues 18 and 19 are valve controlled openings 20 and 21 which communicate with the waste-heat boiler or boilers and dampers 22 and 23 are provided for blocking flues 18 and 19 so that the hot products of combustion cannot escape directly to the stack but must pass first through the waste-heat boiler setting.

The normal positions of the valves when flues 10 and 11 are serving as gas and air inlet flues respectively and flues 12 and 13 as outlet flues for the hot products of combustion are indicated in Diagram 1 of Figure 12. In this figure it will be seen that valves G^r, A^r, A'^s and G'^s are in raised or open position while the remaining valves are closed. In Diagram 4 of Figure 12 the positions of the various valves have been reversed so that the flow through the conduits 10, 11, 12 and 13 is reversed. Diagrams 2 and 3 indicate the positions of the valves at two intermediate stages during the reversal. In Diagram 2 all of the valves are shown closed and in Diagram 3 the air valve to the stack A^s has not yet been opened while valves G^s, A'^r and G'^r are shown in open position. Diagrams 5 and 6 show the two intermediate stages in a second reversal of the valves, from the positions which they appear in Diagram 4 to the positions which they appear in Diagram 1. Diagrams 3 and 6, when taken in connection with Diagrams 4 and 1 show clearly that in the reversals of the furnace the air valves to the stack A^s and A'^s respectively, are the last to be opened. These valves are actually opened only after gas valves to stack G^s and G'^s have been opened in each instance a sufficient time to allow the heated gas in flue 10 or flue 13, as the case may be, to pass to the stack, in order that an explosion may not occur due to the mixing of hot gas and air, as previously described.

The mechanism for effecting automatically this sequence of operations will now be described. Referring to Figures 5 and 6, it will be seen that the valve A^s has its stem

25 connected by means of a cable 26 to a wheel or drum 27 which is fixed on a rotatable shaft 28. Shaft 28 extends through a gear housing 29 and has upon its opposite 5 end a second drum or wheel 30 to which the end of a cable 31 which supports a counter weight 32, is secured. The counter weight is of a size to substantially balance the weight of the valve A^s. A worm wheel in housing 29 meshes with a worm on shaft 33 which is connected to a motor shaft 34 to be driven by motor M^s. The housing 29 and motor M^s are mounted upon a base casting 35 which is supported above the valve upon any suitable framework, such as that illustrated in Figures 5 and 6. It will be understood that each of the valves is provided with a similar motor, these motors being diagrammatically illustrated in Figure 12 at M^F, M^s, N^s, N^F, 15 N'^s, N'^F, M'^s and M'^F, respectively.

In operation, the circuit through motor M^s, for instance, is closed, by mechanism to be hereinafter described, for a sufficient length of time to effect the raising of valve 25 A^s to the desired height, and the circuit is then broken, the worm gear connection between the valve and motor locking the valve against accidental movement when the motor is stopped. At the instant when the 30 circuit through the motor is broken, or shortly thereafter, the counterweight 32 comes to rest upon the stationary support 36, so that the weight of the valve is unbalanced and the motor immediately comes to a full stop. To close the valve the motor is reversed and its rotation continued until the valve is seated, at which time the motor circuit is opened and the motor again stopped.

Referring to Figure 7, a series of spring contacts is indicated at 40, each pair of contacts being connected by suitable wires to one or more of the valve operating motors. The right hand pair of contacts *a* is electrically connected to motors M'^F, N'^F and 45 M^s, as indicated by the printed letters, the second pair of contacts *b* to the motors M'^s, N'^s, N^F and M^F, etc. Extending transversely of spring contacts 40 is a cylinder or drum 41 of insulating material. The ends of 50 spring contacts 40 rest against the surface of this drum, which is mounted to rotate about a fixed axis, and set in the surface of the drum are a plurality of contact plates 42, arranged in pairs, *a'*, *b'*, *c'*, *d'*, *e'* and *f'*, 55 corresponding to the pairs of spring contacts 40.

One plate 42 of each pair is connected by a wire 43 with a contact ring 44 and the other plate of each pair to a contact ring 60 45 by a second wire. Contact rings 44 and 45 are electrically connected by spring contacts 46 and 47, respectively, and wires 48 and 49, to the negative and positive terminals of an electric generator, which may 65 be at any convenient location. Contacts 46

and 47 bear at all times on rings 44 and 45 and it will, therefore, be seen that in a single rotation of drum 41, each of circuits *a*, *b*, *c*, *d*, *e* and *f* will be energized for a length of time depending upon the circumferential lengths of the plates, and the speed of rotation of the drum, inasmuch as each pair of contacts *a'*, *b'*, *c'*, etc. will make contact with the corresponding spring fingers 40 of circuits *a*, *b*, *c*, etc.

The arrangement of motor circuits is such that each motor will be operated twice for a single revolution of drum 41 but the rotations of the armatures will be in opposite directions in successive operations. For instance, motor N^s will be energized when circuit *e* is closed and will again be energized when circuit *f* is closed, but the wires in the two circuits will be reversely connected to the motor armature so that the motor is operated in opposite directions. In this manner the valve A^s is opened and closed and in like manner each of the other valves is operated.

As can be seen from Figure 10, the contact plates *a'*, *b'*, *c'*, etc., are arranged symmetrically in groups of three on opposite sides of drum 41 but each pair of contacts is spaced longitudinally from the adjacent pair.

Also supported on drum 41 are two contact plates 50 and 50', diametrically opposed, and each extending slightly more than one-half of the way around its circumference. Four contact fingers 51, 52, 53 and 54 are arranged in pairs, the first two mentioned being adapted to bear against plate 50 and the last two against plate 50'. Contact fingers 51 and 53 are connected by suitable wires through the motor R to the negative terminal of a generator, and contact fingers 52 and 54 are connected to stationary switch contacts 55 and 56, respectively, either one of which may be connected by a switch S to the positive terminal of the generator. The switch S comprises the main control switch or master switch of the mechanism, inasmuch as it controls the movement of the motor R and hence, the drum 41, which is connected to the motor through the reducing gearing G, so that by manipulating the switch, the motor R may be energized to rotate the drum and open and close the circuits *a*, *b*, *c*, *d*, etc. through the various valve operating motors.

When the drum is in the position illustrated in Figure 7 and the switch S is in its full line position, as shown in this figure, the contact blades 53 and 54 are insulated from each other, as shown in Figure 8, whereas the contact blades 51 and 52 are electrically connected through plate 50. The motor R is, therefore, inactive in this position of the switch but when the switch is moved to its dotted line position, it is energized and causes the rotation of drum 41

at a slow rate of speed. In one particular installation, it was found convenient to design gearing G so that drum 41 rotated through one half of a revolution in thirty-four seconds.

In the operation of the device, however, a movement of switch S to its dotted line position will result only in a movement of drum 41 through 180 degrees, inasmuch as 10 spring fingers 51 and 52 can only contact with plate 50 through one-half of a revolution, after which they pass on to the insulating material and become electrically insulated from each other. This breaks the circuit through motor R and stops the drum's rotation. Returning the switch to the full line position will effect a further rotation of 15 180 degrees, inasmuch as the spring fingers 53 and 54 make contact with plate 50' just before fingers 51 and 52 break contact with plate 50.

The drum 41 comes to rest after each half revolution with all of the circuits a, b, c, d, e and f open so that the valve operating motors are inactive. In Figure 10 is shown the 25 positions of the pairs of contacts a', b', c', etc., at the completion of such a half revolution in the direction of the arrow. The last circuit to be completed was circuit f controlling the motor N^s which operates the air valve to stack A^s. Movement of switch S to its dotted line position, resulting in movement of drum 41 through 180 degrees, results in the closing first of circuit e, then of circuit 30 d, and, after a considerable interval, of circuit c, after which the drum 41 comes to rest. The circumferential lengths of plates 42 determine the intervals during which the motors electrically connected thereto are energized, that is, when considered with the 35 speed of rotation of the drum, and their relative positions on the surface of the drum determine the sequence in which the circuits are closed.

45 It can be seen from Figure 10 that if the speed of rotation of the drum is uniform, that circuits e, d and c are closed the same length of time, which may be five seconds, but that there is a relatively long time interval between the opening of circuit d and the closing of circuit c. Closing of circuit e results in the energization of four valve motors and causes all the valves to be closed, as shown in Diagram 2 of Figure 12. Closing 50 of circuit d results in the opening of valves G'^f, A'^f and G^s, as shown in Diagram 3 and closing of circuit c at a considerable interval thereafter, which may be fifteen seconds, as indicated in Diagram 4 of Figure 12, results 55 in the opening of valve A^s. The drum then comes to rest with all circuits open and awaiting the reversal of switch S. From the foregoing description it will be seen that in a reversal of the furnace the gas valve to 60 the stack G^s is open for a considerable in-

terval, fifteen seconds in this instance, before the adjacent air valve to the stack is open. This prevents intermixture of hot gas and air and obviates the danger of explosions.

Instead of connecting spring contacts 51 and 53 directly to the motor R, they are preferably connected by means of a wire 56' to one terminal of the generator, a magnet coil 57 being, however, included in the circuit. This magnet coil is adapted to attract an armature 58 which comprises a switch controlling the circuit 59 through the armature 60 of the motor. Armature 58 is normally in the position shown in Figure 11 so that circuit 59 is open, a spring 61 serving to maintain the armature in this position. Whenever switch S is reversed, however, magnet 57 is energized, armature 58 is moved to the left to close circuit 59, and the motor R becomes active. At the completion of the revolution of drum 41 through 180 degrees, electromagnet 57 becomes de-energized, circuit 59 is opened and circuit 62 closed. This circuit 62 includes a resistance 63, the effect of which is to oppose a braking force to the rotation of armature 60 to effect the practically instantaneous stopping of the motor.

In the form of the invention above described the opening and closing of the valves is effected by motors, the directions of rotation of which is reversed at each operation. It will be seen from the diagrams of Figure 12 that the wiring is such, as indicated by the + and - signs, that the polarities of the motors' armatures is reversed in opening and closing the valves.

It may be desired to employ motors designed to operate only in one direction, and in Figures 13 to 22 inclusive, valve operating mechanism is described which is adapted to operate in this manner.

In Figure 13 the valve is shown suspended from a crank arm 70 fixed on a rotatable shaft 71 which is supported in housing 72 and which has fixed on its opposite end a crank arm 73 to which the counterweight is hung. Shaft 71 is adapted to be driven through suitable worm gearing from motor 74, which is not reversible. At each energization of this motor by the closing of its circuit, shaft 71 is rotated through 180 degrees, when the motor is deenergized, and the shaft brought to an immediate stop by electro-mechanical mechanism now to be described. The valve is, therefore, seated exactly each time when brought to closed position, as the motor is prevented from overrunning.

Also mounted on shaft 71 and at right angles to crank 70 and 73 is a bar 75. Extending into the path of travel of the ends of this bar (Figure 15) is a plunger 76, and a spring 77 normally holds it in this pos-

tion, to obstruct the passage of bar 75. Plunger 76 has a laterally extending portion 77' at its rear end and which is normally engaged by a hook 78 pivotally secured to the forward end of the armature 79 of a solenoid 80 included in the circuit of motor 74. Hook 78 is connected by a link 81 to a two armed trip lever 82, the forward end of which also lies in the path of rotating bar 75. Assuming the motor to be at rest and the parts to be in the position in which they are illustrated in Figure 15, it will be seen that upon energization of the motor solenoid 80 immediately becomes active and retracts armature 79 which draws with it hook 78 and plunger 76 against the action of spring 77 and armature spring 83. The rearward movement of plunger 76 frees bar 75 which begins to rotate about shaft 71 in the direction of the arrow (Figure 15). After bar 75 has rotated through a short distance, however, it contacts with the forward end of trip lever 82 and depresses the same, thereby raising hook 78 and releasing plunger 76 which immediately flies forward due to the action of spring 77. When shaft 71 has rotated through 180 degrees, the opposite end of lever 75 strikes plunger 76 and further movement is arrested. At, or immediately before this instant, however, the motor circuit has been broken and solenoid 80 de-energized so that the spring 83 thrusts forward the armature 79 and hook 78, which again engages the rear end of the plunger and the mechanism is again set for subsequent operation of the motor. It is impossible, therefore, for shaft 71 to turn through too great an angle, so that the valve will become unseated.

A second form of mechanism for stopping the rotation of shaft 71 at the proper point consists in an electrically operated brake. In Figure 13 a brake wheel is illustrated at 82', and in Figure 14 a brake band 83' is shown, the ends of which are secured to lever 84. This lever is pivoted at 85 and has at its outer end a weight 86. Normally the brake band 83' is held tightly against the brake wheel 82' by weight 86 and this grip of the brake band on the wheel is only interrupted when the brake magnet 87 is energized and lever 84 raised, the magnet being sufficiently strong to overcome the weight 86. A limit switch 88 (Figure 13) is connected by gearing to shaft 71 and becomes operative just as this shaft completes each 180 degrees of rotation. In Figure 20 the armature of motor 74 is indicated diagrammatically at 74', and the brake magnet 87 and limit switch 88 are also indicated. It will be seen that the brake magnet is in series with the limit switch and with the motor, the result being that when the motor is energized, the brake magnet is also energized, lifting rod 84 and permitting free

rotation of the motor armature. As shaft 71 completes its rotation through 180 degrees, switch 88 is operated, the motor circuit broken, the brake magnet de-energized and the armature promptly stopped, so that the valve will be exactly seated.

In Figures 16, 17, 18 and 19 the main control switch S' for this form of the invention, and the secondary circuit making and breaking device are illustrated. The wiring of the control switch S' is exactly as in Figure 7, the motor R' and the gearing G' are also similar, but the drum 41', the contact plates thereon, and the spring contacts with which they cooperate are somewhat different. In this instance, inasmuch as the valve motors are to be driven in one direction only, only one contact ring 44' is used, and instead of pairs of contact plates 42' and pairs of spring fingers 40' for completing the various circuits, each of these circuits is completed by the contact of a single spring contact with a single contact plate. The relative arrangement of the contact plates and of plates 50² and 50³ is, however, the same as before, so that the motors are operated in the same sequence and for the same duration of time. In Figure 22 is shown a series of diagrams corresponding to the diagrams of Figure 12 previously explained, showing the electrical circuits through the several motors in the various steps of the reversal of the valves, there being in this instance no reversal of polarity of the motors.

In Figure 21 is illustrated diagrammatically means for retarding the speed of the motor R' to prolong the interval in which the gas valve to the stack is open and the air valve to the stack is closed, if this is found to be desirable. A resistance 89 in the field of the motor is controlled by rheostat arm 90. A spring 91 normally tends to maintain this arm in such position that the full resistance is in the field circuit. A cam 92, rotatable with drum 41', is adapted to effect movement of the rheostat arm toward the right just after the gas valve to stack has been opened, thereby temporarily cutting out the resistance 89 and reducing the armature speed and hence the drum speed. Other devices of this character might be used to retard the speed of the drum, if desired.

From the foregoing description, it will be apparent that numerous other substitutions and modifications of details might be made without departing from the scope of the invention which is not limited to the several forms disclosed.

The furnace operator has, when the furnace is to be reversed, only to reverse the position of the master switch, calling into operation the circuit making and breaking device. The remainder of the operations is

95

entirely automatic and the valve opening and closing is effected in such manner that all danger of explosion is avoided.

Having thus described the invention what is claimed as new and desired to be secured by Letters Patent is:

1. The combination with a furnace having air and gas regenerators, of valves for controlling passages for conducting products of combustion from the furnace to the regenerators, separate motors for operating the valves, and means for rendering the motors effective to open the valve in the passage leading to the gas regenerator before the valve is opened in the passage leading to the associated air regenerator.

2. Mechanism of the class described including in combination a valve, a rotatable member to which said valve is connected, a motor for rotating said rotatable member and means for stopping the rotation of said rotatable member after it has rotated through 180°.

3. Mechanism of the class described including in combination, a valve, a rotatable member for operating said valve, a motor for rotating said member, and electro-mechanical means for stopping said motor when said member has rotated through 180°.

4. Mechanism of the class described, including in combination, a valve, a rotatable member to which said valve is connected, a motor for rotating said member, a motor circuit, a switch in said motor circuit, means for closing said switch and opening the same when said rotatable member is rotated through substantially 180°, and electro-mechanical means for stopping the rotation of the motor armature when said switch is opened.

5. Mechanism of the class described, including in combination, a valve, a rotatable member to which said valve is connected, a motor for rotating said member, a motor circuit, a switch in said motor circuit, means for closing said switch and opening the same when said rotatable member is rotated through substantially 180°, and an electrically operated brake for stopping the rotation of said motor armature when said switch is opened.

6. Mechanism of the class described including in combination, a valve, a rotatable member connected to said valve for operating the same, a motor for rotating said member, a motor circuit, means for closing said motor circuit and automatically opening the same when said motor has turned said rotatable member through 180°, and electro-mechanical means brought into action by the opening of said circuit for stopping the rotation of the motor armature.

7. In a furnace, the combination of air and gas regenerators connected to first and second ends of the furnace, inlet and out-

let valves for the regenerators, motors connected respectively to the valves for opening and closing the latter, circuits for the motors, means for closing circuits of the motors for the inlet valves of the regenerators at a first end of the furnace and for closing circuits of motors connected to the outlet valves of the regenerators at a second end of the furnace to energize said motors to close the valves, means thereafter effective to close circuits of motors connected to the outlet valves of regenerators at the first end of the furnace and to close the circuit of the motor connected to the outlet valve of the gas regenerator at the second end of the furnace to open said valves, means operative after a predetermined interval to close the circuit of the motor connected to the outlet valve of the air regenerator at the second end of the furnace to open the latter valve, means for operating said circuit closing means, and motion-limiting means associated with the last-named means to render the latter ineffective after the inlet valves at the first-named end of the furnace and the outlet valves at the second end of the furnace are opened.

8. In a furnace, the combination of air and gas regenerators connected to each end of the furnace, air and gas inlet valves for the air and gas regenerators respectively, outlet valves for the regenerators, electric motors operative to open and to close the valves, circuits for the motors including each a pair of contacts, a commutator, contacts on the commutator for closing the circuits of motors associated with the air and gas inlet valves for the regenerators at one end of the furnace and with the outlet valves of the regenerators at the other end of the furnace to render said motors operative for closing said valves, contacts on the commutator disposed rearwardly of the first contacts considering the direction of motion of the commutator for closing circuits of motors for air and gas inlet valves for regenerators at one end of the furnace and for closing a circuit of the motor for the outlet valve of the gas regenerator at the other end of the furnace to energize the motors to open the valves, contact means having its forward end spaced rearwardly of the forward end of the second contacts for closing the circuit of the motor for the outlet valve of the air regenerator at said other end of the furnace to open said valve, means for rotating the commutator, and means for stopping the commutator after air and gas inlet valves are opened for the regenerators at one end and the outlet valves for the regenerators at the other end are opened.

9. In a reversible regenerative furnace, the combination of air and gas regenerators for each end of the furnace, inlet and out-

let valves for the regenerators, electric motors for opening and closing the valves, and switch mechanism to control the operation of said motors and including means whereby an air regenerator outlet valve is opened after the associated gas regenerator outlet valve is opened.

10. In a reversible regenerative furnace, the combination of air and gas regenerators for each end of the furnace, inlet and outlet valves for the regenerators, electric motors for opening and closing the valves, switch mechanism to control the operation of said motors and including means whereby an air regenerator outlet valve is opened after an associated gas regenerator outlet valve is opened, a motor for operating the switch mechanism, and means for stopping the motor after the switch mechanism has been operated to open air inlet valves at one end of the furnace, to close outlet valves at that end, to open the regenerator outlet valves at the other end and to close the regenerator inlet valves at the latter end.

11. In a regenerative furnace, the combination of air and gas regenerators for each end of the furnace, inlet and outlet valves for the regenerators, means for producing cyclic operation of the valves wherein an air regenerator outlet valve is opened later than its associated gas regenerator outlet valve, said means including a motor for each valve, circuits for the motors including pairs of contacts, a commutator having contacts for making and breaking the circuits, a motor for driving the commutator, limit switch mechanism for breaking the circuit of the last-named motor after a cycle of operation of said valves is completed, and means to apply a braking effect to said motor upon the breaking of its circuit and the completion of a cycle of operation of said valves.

12. In a regenerative furnace, the combination of air and gas regenerators for each end of the furnace, inlet and outlet valves for the regenerators, means to secure reversible cycle operation of the valves wherein an air regenerator outlet valve is opened after an associated gas regenerator outlet valve is opened, said means including a reversible motor for each valve, circuits for

the motors, switch mechanism for making and breaking the circuits and including a movable element, a motor for driving the movable element of the switch mechanism, overlapping contacts carried by said movable element, a pair of contacts adapted to engage each of the overlapping contacts, a master switch for completing a circuit for the last-named motor through a pair of contacts in engagement with an overlapping contact to operate said motor to move the movable switch element, and braking means rendered effective by the disengagement of an overlapping contact from a pair of active contacts to stop the motor with the other pair of contacts in engagement with the other overlapping contact upon the completion of a cycle of valve operation.

13. In a regenerative furnace, the combination of air and gas regenerators for each end of the furnace, inlet and outlet valves for the regenerators, means to secure reversible cyclic operation of the valves wherein an air regenerator outlet valve is opened after an associated gas regenerator outlet valve is opened, said means including a reversible motor for each valve, circuits for the motors, switch mechanism for making and breaking the circuits of said motors to secure cyclic operation of the valves, said switch mechanism including a rotary drum having contacts thereon for making and breaking the motor circuits, a motor for driving the drum, overlapping segmental contacts carried by the drum, a pair of contacts adapted to engage with each of said overlapping segmental contacts, a switch for completing a circuit through a pair of contacts in engagement with a segmental contact and said motor to operate the latter to rotate the drum, and electro-dynamic braking means rendered effective by a segmental contact passing out of engagement with a pair of contacts in order to stop the motor with the other pair of contacts in engagement with the other segmental contact upon completion of a cycle of valve operation.

In testimony whereof I hereunto affix my signature.

CHARLES PRENTICE TURNER.
